MEANS FOR CONTROLLING AIR CONDUITS

Lawrence H. Bingham, Bayside, N. Y.

Application July 12, 1938, Serial No. 218,808

16 Claims. (Cl. 137—161)

This invention relates to means for controlling the flow of air through the conduits of air conditioning systems or similar conduits, and it is an object of the invention to provide a damper for this purpose, which may be mounted in and removed from a conduit as a unit.

It has been the customary practice to control the flow of air through the conduits of an air conditioning system at a point adjacent to the air conditioning apparatus and remote from the registers in the conduits for discharging the conditioned air into the rooms of a building. Whether the proper amount of air is passing through a conduit and entering a predetermined room is dependent upon the size of the room and the temperature to be maintained therein, and is determined at the register of the conduit in said room by the use of a velocimeter or other suitable instrument. By the practice of having the means for controlling, such as a damper in the conduit, at a point remote from the point at which the flow of air is measured, it is necessary to constantly travel between said points until the correct amount of air is discharged from the register. This regulating of the discharge of conditioned air at the register in each room of a building is called balancing an air conditioning system, and the balancing of an air conditioning system of an ordinary home by the method hereinbefore described will require the services of two men for a full working day.

It is another object of the invention to overcome the above disadvantage by providing control means for air conduits of conditioning systems which are readily adjustable at the registers of said conduits, whereby one man will be able to balance an air conditioning system within a short period of time.

It is another object of invention to provide air control means and a register for the discharge opening of an air conduit as a unit, whereby the control means and register may be mounted in and removed from the discharge opening at the same time.

It is a further object of the invention to provide air control means in a conduit adapted to be automatically actuated to close the conduit when a fire develops in the conduit.

A still further object of the invention is to provide air control means which will not cause air eddies in partially closed positions.

Further objects and advantages of the invention will be pointed out in the detailed description of the invention.

In the drawing accompanying and forming a

part of this application, Figure 1 is an elevational view of control means constituting an embodiment of the invention and showing the same in normally open position looking from the interior of a conduit.

Figure 2 is a sectional view of a conduit at the discharge or register portion thereof showing the control means mounted adjacent to the discharge opening in the conduit and means to actuate said control means below the discharge opening.

Figure 3 is a view similar to Figure 2 with portion of the discharge opening broken away and showing the control means connected to a register and a portion of the control means in position closing the conduit after fire has developed in the conduit.

Figure 4 is a fragmentary cross sectional view, on an enlarged scale, taken on the line 4—4 of Figure 2 looking in the direction of the arrows, to show the pivotal and sliding mounting of a portion of the control means.

Figure 5 is fragmentary prospective view of a portion of a carrier for the control means showing the pivotal and sliding mounting of the control means thereon and an abutment for limiting the movement of the control means.

In carrying out the invention, the embodiment thereof is illustrated in the accompanying drawing in conjunction with a conduit 6 forming a part of an air conditioning system and of uninflammable material, such as sheet metal, and of rectangular shape in cross section having one end arranged with a laterally extending portion having an opening, as at 7 in Figure 2, to constitute the discharge or outlet for the conditioned air from or the air intake of an air conditioning apparatus, to which apparatus the opposite end of the conduit is adapted to be connected in any suitable manner, not shown. The air conditioning apparatus will have as many conduits as there are rooms to be conditioned. The discharge opening of each conduit is arranged with a laterally extending flange 8 to facilitate the mounting of the discharge end of each conduit in the wall of a room and the mounting in said opening of a register 9 having louvers 10 to control the direction and amount of flow of conditioned air from the conduit and a lateral flange 11 to engage the flange 8 of the opening 7 and permit securing of the register to the conduit, as by screws, not shown.

The means to control the flow of conditioned air from the body of the conduit to the discharge opening is in the form of a hinged damper comprising a pair of plates 12, 13 of uninflammable

material, such as sheet metal, and of a width slightly less than the width of the conduit 6 to control the flow of air for the entire width of the conduit without interfering with the adjustment of the damper. The plate 12 is shown to be of less length than the plate 13, but both plates may be of the same length without affecting the function of the damper. The plates 12, 13 are pivotally connected to each other by flexible material shown in the drawing to be in the form of a strip 14 of a length substantially the width of the plates, but said pivotal connection may be formed of several narrow strips of flexible material fixed at opposite edge portions to the adjoining marginal portions of the plates 12, 13 at suitable spaced points of said marginal portions. The hinge strip 14 is secured to the adjoining marginal portions of the plates 12, 13 by strips 15 of durable material and rivets 16, as shown in Figure 1, the strips 15 preventing the hinge tearing from the plates 12, 13. The hinge 14 is also of inflammable or fusible material, such as fabric or "Cellophane," whereby the hinge will be destroyed by a fire or intense heat in the conduit and the plates 12, 13 separated for a purpose to be hereinafter described.

The damper plates 12, 13 are supported in the conduit 6 by a carrier comprising a sheet 17 of relatively stiff material, such as metal, having the opposite side portions folded over to form opposing grooves 18, the sheet 17 being of a width to position the folded sides thereof against the interior face of the side walls of the conduit 6, as shown in Figure 1. The damper plate 13 is slidably and pivotally mounted in the grooves 18 by pins 19 extending laterally from the opposite sides of the plate to engage the grooves and secured in an arcuate groove 20 in the end portion of the plate 13 opposite the end arranged with the hinge 14 by any suitable means, such as solder as shown at 21 in Figure 5. The engagement of the pins 19 in the grooves 18 will permit the grooved end 20 of the plate 13 to move longitudinally of the carrier 17 and the end of the plate 13 fixed to the hinge 14 to move transversely of the conduit 6. One end portion of the carrier sheet 17 is arranged to pivotally support the damper plate 12 by a hinge of suitable form and shown as a strip 22 of flexible material, such as fabric, having one longitudinal margin secured to the sheet 17 by clamping said portion in a folded over portion of the end of said sheet, as at 23, and the opposite longitudinal margin of the hinge strip 22 being secured to the plate 12 by a strip 24 of durable material and rivets 25, as shown in Figure 1. The hinge 22 may comprise a series of narrow strips of material fixed to the folded over end 23 and plate 12 at spaced points, as pointed out in connection with the hinge 14. The length of the sheet 17 in assembled condition is substantially the same as the assembled damper, as shown in Figures 1 and 2, and the end portion of the sheet 17 opposite the folded over end portion 23 is arranged with a laterally extending flange 26 to engage the grooved end 20 of the damper plate 13 and limit the movement of said plate, as hereinafter described.

The damper carrier 17 is supported on the inner face of one of the longitudinal walls of the conduit in juxtaposed relation to said face with the grooves 18 and flange 26 exposed. The carrier sheet may be secured to the conduit in any suitable manner and is shown in the present embodiment as being secured at the folded over

end 23 by rivets engaged in the wall of the conduit, the sheet 17 and the hinge 23, as shown at 27, whereby the sheet 17 is secured to the conduit wall and the hinge 22 is secured to the sheet. Screws may be substituted for the rivets 5 27 to permit the releasable mounting of the damper in the conduit. In Figure 1, the damper is shown mounted in a straight section of the conduit 6 remote from the register 9 and which may be adjacent to the air conditioning apparatus in accordance with the common practice hereinbefore described, and in such latter case, the entire body of the sheet 17 is straight. In Figures 2 and 3, the damper is mounted at the air outlet portion 7 of the conduit, and in which case, the folded end portion 23 of the sheet 17 is bent laterally to engage the inner face of the outlet portion, as shown at 28. In Figure 2, the fastening means 27 is engaged in the portion 1, portion 28 and hinge 22, so that the damper is mounted independently of the register 9, whereas in Figure 3, the damper is connected to the register 9 by engaging the fastening means 27 in the register 9, portion 23 and hinge 22, so that the register and damper may be engaged in and removed from the conduit 6 as a unit. The outlet 7 of the conduit 6 is of slightly greater height than the register 9 to accommodate the folded end 23 of the sheet 17, as shown in Figures 2 and 3. 10 15 20 25 30 35 40 45 50 55 60 65 70 75 80 85 90 95

The damper plates 12, 13 are yieldingly maintained in juxtaposed relation to the sheet 17 by a spring 29 releasably connected at one end to the plate 13 adjacent the hinge 14, as at 30, with the opposite end releasably connected to an anchorage which may be a portion 31 depending from the grooved end 26 of the sheet 17 and having a lateral ear arranged to releasably engage said opposite end of the spring, as at 32. In mounting the damper in a vertical portion of 40 the conduit 6, as at the outlet portion 7, the spring 29 is not essential in maintaining the damper plates 12, 13 juxtaposed to the carrier 17, as the weight of said plates and the force of gravity will maintain the damper in such 45 position, and the principal function of the spring 29 in such cases is to urge the end of the plate 13 arranged with hinge 14 toward the wall of the conduit opposite the wall to which the carrier 17 is juxtaposed. The purpose of this function of 50 the spring 29 is to automatically close the conduit 6 from the outlet 7 should a fire develop in the air conditioning apparatus and travel through the conduit, which closing of the conduit will prevent the fire entering a room through the 55 outlet 7. This is accomplished by the fire destroying the hinge 14, which is of inflammable material, and the spring 29 actuating the free end of the damper plate 13 into position to close the conduit, as shown in Figure 3. In the Figure 60 65 70 75 80 85 90 95 disclosure of the invention, the damper was in position partially closing the passage of the conduit, as shown in dotted lines in Figure 2, when the fire destroyed the hinge 14, and by the action of the spring, the plate 13 was positioned with the grooved end 20 abutting the flange 26 and the free end abutting the opposite wall of the conduit. The automatic closing of the damper may be performed by springs coiled around the pins 19 having one end fixed to the damper 70 plate 13 and the other ends engaging the sheet 17, so that a yielding force is exerted on the plate 13 to urge the hinged end thereof from the sheet 17 when the hinge 14 is destroyed by fire, instead of the spring 29. The springs will not actuate 75

the plates 12, 13 into the passage of the conduit 6 unless the hinge 14 is destroyed due to the mounting of the damper plates 12, 13 at the opposite ends thereof, as at 19 and 22.

5 In the normal position of the damper plates 12, 13, juxtaposed to the carrier 17, the passage of the conduit 6 is fully open to the outlet 7, so that the full output of the air conditioning apparatus is delivered to the room in which the 10 register is located. To regulate the delivery of conditioned air and reduce the normal flow thereof to the outlet 7, the hinged portion 14 of the plates 12, 13 is adjusted toward the opposite wall of the conduit and into the passage 15 by means adjustable from the exterior of the conduit and adapted to engage the plate 12, comprising a headed screw 33 adjustably mounted in the sheet 17 and extended through the sheet and adjacent wall of the conduit 6 with 20 the head of the screw exterior of the conduit and the free end adapted to engage the plate 12 adjacent the hinge 22, so that adjustment of the screw into the conduit will move the plate 12 on its hinge 22 and move the pins 19 from 25 the flange 26 with the hinge 14 forming an angle, as shown in the dotted line position of the damper in Figure 2. The adjusted positions of the damper plates into the passage of the conduit will not cause eddies of air in said passage with 30 resulting noise, as the inclining wall and rounded angle formed by the hinge 14 will form a streamline passage for the air passing to the outlet 7. The adjustment of the screw in a direction out of the conduit 6 will permit the damper plates 35 12, 13 to assume their normal position juxtaposed to the sheet 17 by the force of gravity or the spring 29. If the damper is mounted at the outlet portion 7 of the conduit, the adjustment screw 33 will be mounted adjacent to said outlet 40 portion and the portions of the flanges 8, 11 in alignment with the screw are arranged with an opening 34 to permit engagement of the head of the screw with a suitable tool to actuate the screw, and the screw head may be of specific 45 design requiring a special tool for engaging the same to permit only designated persons to adjust the damper. The screw 33 may be retained in adjusted position by a lock nut 35. In the mounting of the damper, as shown in Figures 2 50 and 3, the amount of air being discharged by the conduit is tested at the register 9, and if the amount is not correct, the damper is adjusted by the screw 33 until the correct amount is discharged, without leaving the register, which 55 will save considerable time in checking all the air outlets of a complete air conditioning system.

The automatic closing of the damper plate 13, when the hinge 14 has been destroyed by fire, 60 may be accomplished by providing a weight at the end of the plate 13 adjacent to the hinge 14, as by using a heavy strip 15, so that the weight will force said end of the plate into engagement with the wall of the conduit opposite the wall on which the damper is mounted without the use of springs.

Having thus described my invention, I claim:

1. In a damper for air conduits, a plate pivotally mounted on a wall of a conduit, a second 70 plate pivotally and slidably mounted on the same wall and pivotally connected to the first plate, and means adjustably mounted on said wall of the conduit adapted to abut the first plate and adjust the pivotal connection of the plates toward the opposite wall of the conduit to

2. In a damper for air conduits, a plate pivotally mounted on a wall of a conduit, a second plate pivotally and slidably mounted on the same wall and pivotally connected to the first plate, means connected to one of said plates and the conduit to yieldingly position the plates in juxtaposed relation to said wall, and means adjustably mounted on said wall of the conduit to abut the first plate and adjust the pivotal connection of the plates toward the opposite wall of the conduit against the force of the yielding means, said yielding means adjusting the plates toward the wall on which they are mounted when the adjusting means is adjusted out of abutting relation with the first plate. 15

3. In a damper for air conduits, a plate pivotally mounted on a wall of a conduit, said wall of the conduit being arranged with opposed grooves at the adjacent walls, a second plate pivotally connected to the first plate and having means slidably and pivotally engaging the grooves, a spring connected to the conduit and second plate to urge the plates in position juxtaposed to the conduit wall between the grooves thereof, and means adjustably mounted in said conduit wall and adapted to abut the first plate and adjust the pivotal connection of the plates toward the wall of the conduit opposite the wall arranged with the grooves against the force of the spring. 30

4. In a damper for air conduits, a plate pivotally mounted on a wall of a conduit, a sheet of relatively stiff material having grooves at opposite sides and juxtaposed to said wall of the conduit adjacent to the mounting of the plate 35 with the grooves adjacent the walls adjoining the wall to which the sheet is juxtaposed, a second plate having means projecting from opposite sides thereof to slidably and pivotally engage the grooves and pivotally connected to the first plate, a spring connected to the sheet and second plate adapted to urge the plates to a position juxtaposed to the sheet, and means adjustably mounted in the juxtaposed conduit wall and sheet to abut the first plate and adapted 40 to adjust the pivotal connection of the plates toward the wall of the conduit opposite the sheet to restrict the passage of air through the conduit. 45

5. A damper as claimed in claim 4, wherein the end of the sheet opposite the end adjacent the first plate is arranged with a lateral flange 50 to limit the movement of the second plate.

6. In a damper for air conduits, a plate of unflammable material pivotally mounted at one end on a wall of a conduit, a second plate of unflammable material slidably and pivotally mounted at one end on said wall of the conduit, a hinge member of inflammable material connecting the free ends of the plates, and means connected to the conduit and second plate 60 adapted to move the hinged end of the second plate toward the wall of the conduit opposite the wall on which the plates are mounted, burning of the inflammable hinge by a fire in the conduit causing the disconnecting of the plates and said means to move and engage the hinged end of the second plate with the opposite wall of the conduit and close the conduit. 65

7. A damper for air conduits as claimed in 70 claim 6, wherein the inflammable hinge of the plates comprises a strip of flexible material fixed at opposite portions to the free ends of the plates.

8. In a damper for air conduits, a plate pivotally mounted at one end on a wall of a conduit, 75

- said wall adjacent to the mounting of the plate being arranged with a pair of opposed grooves extending parallel and adjacent to the adjoining walls of the conduit and a lateral flange extending 5 between the ends of the grooves remote from the mounting of the plate, a second plate of uninflammable material having means projecting from the sides at one end thereof to slidably and pivotally engage the grooves, a strip of inflammable material fixed to the free ends of the plates to pivotally connect said plates, and a spring connected to the conduit and second plate to urge the plates toward the wall of the conduit arranged with the grooves and flange and 10 urge the means of the second plate engaged in the grooves into engagement with the flange, burning of the inflammable strip by a fire in the conduit causing the disconnecting of the plates and the positioning of the second plate across 15 the conduit under the influence of the spring.
9. In a damper for air conduits having laterally extending air openings, a sheet of relatively stiff material having grooves on opposite sides and a laterally extending end portion secured 20 to a portion of an air opening of a conduit with the grooves adjacent to the walls of the conduit at the sides of the opening, a plate pivotally mounted at one end on the lateral end portion of the sheet, a second plate having means projecting from the sides at one end thereof slidably and pivotally engaged in the grooves, flexible material fixed to the free ends of the plates to pivotally connect said plates to each other, yielding means connected to the second plate and 25 sheet adapted to position the plates in juxtaposed relation to the sheet between the grooves and position the pivotally connected end of the second plate to close the conduit from the opening when the flexible material is parted between 30 the plates.
10. A damper for air conduits having laterally extending air openings as claimed in claim 9, wherein the flexible material is inflammable and is adapted to be parted by a fire in the conduit, 35 the positioning of the second plate to close the conduit preventing fire passing through the opening.
11. A damper for air conduits having laterally extending air openings as claimed in claim 9, 40 wherein the first plate is pivotally mounted on the lateral end portion of the sheet by flexible material fixed at opposite portions to the first plate and the lateral end portion of the sheet.
12. In a damper for air conduits having laterally extending air openings as claimed in claim 9, 45 a member adjustably mounted in the wall of the conduit and sheet adjacent to the opening with a portion extending exteriorly of the conduit and a portion extending into the conduit to abut the first plate, whereby movement of said member 50

into the conduit will adjust the pivotally connected ends of the plates toward the opposite wall of the conduit and restrict the passage of the conduit.

13. In a damper for air conduits having laterally extending air openings, a register for regulating an opening of a conduit removably mounted in the opening, a sheet of relatively stiff material having grooves at the opposite sides and a laterally extending end portion fixed to the register with the sheet juxtaposed to the wall of the conduit arranged with the opening, a plate pivotally mounted on the laterally extending end portion of the sheet, a second plate having pins extending laterally from an end portion of said plate slidably and pivotally engaged in the grooves of the sheet, flexible material fixed at opposite portions to the free ends of the plates to pivotally connect the plates, and a screw adjustably mounted to extend through the wall of the conduit adjacent the opening and having a portion extending exteriorly of the conduit and a portion abutting the first plate, whereby movement of the screw into the conduit will adjust the pivotal connection of the plates toward the wall of the conduit opposite the opening and restrict the passage of the conduit.

14. In a damper for air conduits having laterally extending air openings as claimed in claim 13, a spring fixed to the sheet and the second plate adjacent the flexible material to normally position the plates juxtaposed to the sheet and urge the end of the second plate connected to the first plate toward the wall of the conduit opposite the sheet when the flexible material is parted.

15. In a damper for air conduits, a plate of uninflammable material pivotally mounted at one end on a wall of a conduit, a second plate of uninflammable material slidably and pivotally mounted at one end on said wall of the conduit, and a hinge member of inflammable material connecting the free ends of the plates, whereby the burning of the inflammable hinge by a fire in the conduit will cause disconnecting of the plates and the positioning of the hinged end of the second plate into engagement with the opposite wall of the conduit to close the conduit.

16. In a damper for air conduits, a plate pivotally mounted at one end on a wall of a conduit, a second plate slidably and pivotally mounted at one end on said wall of the conduit, and a hinge member of fusible material connecting the free ends of the plates, whereby fusing of the hinge member by intense heat in the conduit will cause the disconnecting of the plates and the positioning of the hinged end of the second plate into engagement with the opposite wall of the conduit to close the conduit.

LAWRENCE H. BINGHAM. 60
